UNITED STATES PATENT OFFICE.

ALBERT F. DAUM, OF PITTSBURGH, PENNSYLVANIA.

FUSE.

1,378,329.

Specification of Letters Patent. Patented May 17, 1921.

Application filed December 10, 1918. Serial No. 266,057.

To all whom it may concern:

Be it known that I, ALBERT F. DAUM, a citizen of the United States, residing at Pittsburgh, in the county of Allegheny and 5 State of Pennsylvania, have invented certain new and useful Improvements in Fuses, of which the following is a specification.

This invention relates to improvements in fuses of the inclosed type, being particularly adaptable for use in connection with 10 such fuses having a renewable or refillable characteristic.

Inclosed fuses, generally in the form of tubular casings carrying terminals at the 15 ends in the form of caps or other metallic elements, with the fusible element connecting such terminals either direct or through connections, universally provide metallic elements of stable material both internally 20 and externally of the insulating casing—the fusible element itself being considered as unstable in the presence of predetermined temperatures. In some forms, the fusible element is secured to the internal stable 25 formation; in other forms the element is clamped or otherwise secured in contact with the stable formation, the general purpose being to not only secure the element in position but, in addition, to provide an extended 30 heat-dissipating zone at the ends of the casing serviceable to prevent blowing the element adjacent the end, and thereby tending to restrict the point of disruption more or less remote from such ends. This necessitates the use of stable metallic structures as essential elements of the fuse, thereby 35 providing a material cost factor in the manufacture of the fuse. One of the objects of the present invention is to eliminate this cost to a considerable extent by dispensing with these stable structures, thus not only 40 reducing the fuse cost as a whole, but also providing a saving of metallic materials heretofore required in fuse production.

Another characteristic of such prior fuses is that while such zones may tend to restrict the point of disruption to an intermediate point of the casing, this safety factor is present only where no arc is left by the 45 disrupting action, it being readily understood that the formation of an arc simply acts to maintain the circuit with the heat factor active in the form of the arc, so that disruption continues with an increase in the 50 length of the arc, until the latter reaches the stable structures, bringing about con-

ditions for sustaining the arc between these structures. To prevent this action it has been the custom to pack the casing with a suitable filler, the purpose being to quench 60 the arc through the presence of the filler, thus preventing the arc reaching the stable structures. The use of a filler not only adds to the cost of manufacture, but where the fuse is of the renewable type, difficulty or 65 time loss is present when a new element is to be inserted since this packing action must be had with each re-filling operation. Another object of the invention is, therefore to eliminate this difficulty by eliminating the 70 necessity for using a filler and at the same time provide against any formed arc reaching any stable metallic structure. This object is attained by leading the ends of the fusible element to the exterior of the fuse 75 in such manner as to produce an efficient barrier between the internal and external portions of the element, such barrier serving to prevent the arc from reaching the exterior portions. This barrier effect may be 80 produced in different ways based generally on the fact that the direction of lead of the end portions of the element is angular to that of the intermediate portion, so that these end portions emerge through the side 85 of the fuse—either through the casing or the end closure (both of insulating material)—thus interposing the latter in the path of any arc, the latter being required to follow the end portions on to the exterior of the fuse—conditions conducive to the quenching 90 of the arc. The external ends may be connected to terminals of stable material, 95 but it is preferred to employ these ends as the terminals by simply carrying them circumferentially of the fuse, in which case the fusible element may form the only metallic portion of the fuse.

The invention is applicable for use with inclosed (non-renewable) or renewable fuses, being of a form which requires no difficult operations in renewing the element.

Another object is to provide a structure 105 of this type which is indicating in operation.

Other objects are to provide a construction which is simple and efficient in operation, durable in construction, and which can be manufactured at low cost.

To these and other ends, the nature of which will be readily understood as the in-

100

105

110

vention is hereinafter disclosed, said invention consists in the improved construction and combination of parts hereinafter fully described, illustrated in the accompanying drawings, and more particularly pointed out in the appended claims.

In the accompanying drawings, in which similar reference characters indicate similar parts in each of the views,—

10 Figure 1 is a view, partly in section and partly in elevation, showing various ways in which the present invention may be carried into effect.

15 Fig. 2 is a side elevation of a fuse structure illustrating a way in which the end terminals may be located on the fuse.

Fig. 3 is a perspective view of one of the fusible elements in condition for insertion.

20 Fig. 4 is a perspective view illustrating the manner in which the curled end of the fuse may be treated to position it within the fuse casing.

25 A preferred form of a non-indicating fuse is illustrated in Fig. 2, this particular form being shown at A in Fig. 1. In this form, 10 indicates a tubular casing of suitable length and formed of insulating material. 11 indicates one form of end plug or closure which may be employed, the plug having an 30 external portion 11^a and a reduced portion 11^b which enters the end of the casing; the plug is preferably formed of suitable insulating material. The fusible element is in strip form and indicated at 12.

35 As shown in Fig. 1 at A, casing 10 may be provided with a slit or kerf 10^a extending longitudinally from the open end of the casing, the length of the slit preferably slightly exceeding the width of the fusible element.

40 Plug portion 11^b is also slotted, as at 11^c (forms A and B of Fig. 1) the slits of the plug and casing being alined when assembled.

45 Assuming both ends of the casing to be of similar formation, the fusible element when in position to complete the fuse, has an intermediate portion 12^a of a length substantially equal to the length of the casing, and two end portions 12^b extending transversely 50 of the direction of length of the intermediate portion and extending through slits 10^a to the exterior of the casing and simply laid circumferentially around such exterior, extending but part way around or entirely 55 around as may be desired.

60 The change in direction of the fusible element may be provided in any suitable manner, a preferred way being to fold the element upon itself at right angles at this point, thus producing a double thickness of generally triangular form at this point. As this bend is made at a point approximately the end of the casing, it will be understood that this doubled portion is located within 65 slit 11^c as is that portion of the strip leading

from the bend to slit 10^a. With the element properly positioned and the plugs inserted, the latter are preferably secured in position in suitable manner, as by the use of pins 13 which may extend entirely through the 70 fuse and which may be of suitable material, insulating or otherwise. Pins 13 may pass through the fusible element, as in form A or may be independent of the element, as in form C.

75 As will be understood, the bends may be provided at points spaced a greater distance than the length of the casing, to take care of the difficulty of passing one end of the element through the casing, but such arrangement tends to buckle the intermediate portion 12^a where both ends of the casing are slotted, as in Fig. 2. This difficulty is not materially present where an end plug and element position is had as in form B—presently described, so that the inserted end of the strip will remain unbent until after it has passed through the casing and the opposite end seated.

80 However, where the form of Fig. 2 is employed, the element may be inserted by following the practice now described. After the bends have been made at the proper points, the end to be inserted is curled or coiled as in Figs. 3 and 4, thus reducing the 85 end portion to a form which will pass through the casing without affecting the bend. The uncurled end is then placed within the slit 11^c of an end plug 11 and the curled end of the fusible element introduced and 90 passed through the casing as in Fig. 4, this action bringing the plug portion 11^b within the casing, it being understood that as the latter passes to position it will be introduced in such manner that the projecting end portion 95 will pass into slit 10^a of the casing, by alining slit 11^c with slit 10^a. If desired, pin 13 may now be placed in position to locate the plug seated; if the pin passes through the strip, its introduction will provide the 100 opening for the passage of the pin. This secures one end of the fusible element, with the opposite end projecting from the casing 105 in curl form. This curl is then straightened out in such way as to bring its transverse 110 portion through slit 10^a, after which the remaining end plug may be inserted, positioning its slit 11^c in such manner as to receive the positioned end portion of the element, 115 after which the pin 13 is inserted. The projecting ends are then simply placed about the casing, completing the fuse, the terminals of which are provided by these external strip portions which are brought into contact 120 with the clip fingers of the fuse support.

125 From this it will be seen that the intermediate portion of the element—which may be slotted or kerfed at an intermediate point, if desired, this being a well known practice to locate the point of disruption—extends 130

from one end plug to the other, entering into the slits 11^c at the ends, and then continuing transversely through slits 10^a to the exterior. Should, therefore, an arc be formed as the 5 element disrupts, the continued destruction of the unstable element under a sustained arc, may continue until it reaches the plug, whereupon it would be required to pass into the slit 11^c, longitudinally of the casing and 10 then transversely through this slit and slit 10^a before the arc could reach the stable metallic clip contacts. Obviously the change from the open space of the interior of the casing into the confined slit spaces, together 15 with the fact that the walls of the slits form parts of comparatively large elements normally cool and tending to absorb heat, will prevent the arc from following this course, these parts having the effect of a barrier 20 against the passage of the arc although permitting the free passage of the fusible element itself.

It is necessary only to remove the pins by driving or pushing them out of the casing to permit the plugs to be removed and expose the interior of the casing for renewal purposes.

If desired, one or both ends of the fuse may be formed as shown at B, wherein plug 30 portion 11^a is of greatly increased thickness, with slit 11^c extending into this portion. In this form, the element end portion is brought out through slit 11^c and applied externally of the plug instead of the 35 casing, the pin passing through portion 11^b as before, either through the strip as shown in form B or by-passing the strip as in form C. Obviously, one end may employ form A, the opposite end employing form 40 B, thus producing a fuse of the combination of forms A and B.

The principles of forms A or B can be employed for indicating purposes. For instance, form E differs from form A in employing elongated slots 10^b in the casing in place of the simple openings for pin 13; the pin occupies the inner end of the slots when the plug is in normal position. With the opposite end of the fuse of the type 50 of forms A or B, the pressures produced within the casing by disruption are free to be exerted on the plug of form E which is thus moved outwardly within the limits of the length of the slots 10^b. As will be 55 understood, the plug is anchored in its inner position by driving the pin through the fusible element within slit 11^c for the ends of pin 13. Obviously, the shifted position of the plug will afford visual indication that 60 the fusible element has been disrupted, since the distance between the pins in normal position must have increased to permit one pin to shift longitudinally and this can take place only in the presence of a break in the 65 strip intermediate the pins.

The pressure effects of the gases may be increased by spring action, if desired—and this is preferred—by increasing the length of portion 11^b, as in form D, and placing a coil spring 14 about the projecting portion, utilizing slots 10^b in the casing. By forcing the plug inwardly to compress the spring before inserting the pin, and locating the latter at the inner end of the slot, the engagement of pin and element as the 70 pin passes through the latter, prevents the spring from expanding, thus tending to place the element under tension. When disruption takes place the spring rapidly expands by reason of the fact that the holding means—the fusible strip—has been disrupted, so that the tension of the spring can become active, pin 13 shifting within slots 10^b, this shifting of the plug serving to not only provide the indicating feature, but in 75 addition tending to break down an incipient arc.

As shown in form F, the features of form D can be employed in connection with the type indicated in form B, the plug being 80 set as in form D.

Obviously, each of the forms shown may be employed in duplicate form at the opposite ends of the casing, or either form may be employed with either of the remaining 95 forms, as may be found desirable or preferable. In any combination thus produced, however, there is found the same general underlying feature of the end portions of the fusible element extending in directions 100 angular to the direction of length of the intermediate portion, and these external end portions are protected by the barrier effect referred to above. In addition, each form has the external portions operative as terminals, and this is true even if these external portions are secured to metallic portions of stable material external of the fuse. And where pins 13 are of insulating material, the fusible element forms the only metallic material present within the outer surface of the fuse; where metallic pins are employed, their particular location relative to the inner ends of slits 11^c is such as to practically prevent the arc from reaching 115 them.

As will be seen, the casing and plugs are of simple configuration, readily produced from insulating material and at relatively low cost, and the same is true of pins 13 120 and springs 14, if employed. And since the fusible element is a simple strip of unstable material, it can be taken from a roll of such material, the disrupting point structure produced by slotting or kerfing and inserted by a simple operation. Since the arrangement is such as to prevent the continuation of the arc through the plug slits, or the plug and casing slits, the presence 125 of a sustaining arc at the instant of dis- 130

ruption becomes more or less immaterial, since the destruction of the intermediate portion of the fusible element can be had without damage—hence there is no requirement of the use of an arc-quenching filler, although it may be employed if desired.

Obviously, under present day conditions of a shortage of metal of the type generally utilized in the formation of the stable metallic structures, the entire elimination of the latter makes possible the production of a fuse even under such conditions.

While I have herein shown and described various ways in which the general principles of the present invention may be produced and employed, it will be readily understood that changes or modifications therein may be found essential or desirable to meet the exigencies of use or service or preferences of users, and I desire to be understood as reserving the right to make any and all such changes or modifications as may be found desirable or necessary, in so far as the same may fall within the broad spirit and scope of the invention as expressed in the accompanying claims when broadly construed.

Having thus described my invention, what I claim as new is:

1. An inclosed fuse comprising a tubular casing of insulating material, end closures therefor, and a fusible element of strip form having its end portions exposed externally and circumferentially of the fuse and an intermediate portion traversing the interior of the casing in the direction of casing length.

2. A refillable fuse comprising a tubular casing of insulating material, removable end closures therefor, and a fusible element of strip form having its end portions exposed externally and circumferentially of the fuse and an intermediate portion traversing the casing in the direction of casing length.

3. An inclosed fuse comprising a tubular casing of insulating material, end closures therefor of insulating material, and a fusible element of strip form having its end portions exposed externally and circumferentially of the fuse and an intermediate portion traversing the interior of the casing in the direction of casing length.

4. A refillable fuse comprising a tubular casing of insulating material, removable end closures therefor, and a fusible element of strip form having an intermediate portion traversing the casing in the direction of casing length, said strip being bent to lead its end portions in directions angular to such intermediate portion to locate such portions externally exposed on circumferential portions of the fuse.

5. A fuse of the type disclosed in claim 4 characterized in that the bends are located in unexposed positions.

6. In a refillable fuse, a tubular casing of insulating material and having a slot extending longitudinally of an end of the casing, a fusible element extending longitudinally of the interior of the casing and having an end portion projecting through said slot and externally exposed on the outer face of the casing, and means for closing the end of the casing.

7. In a refillable fuse, a tubular casing of insulating material and having a slit extending longitudinally of an end of the casing, a fusible element extending longitudinally of the interior of the casing and having an end portion projecting through said slit and externally exposed on the outer face of the casing with the exposed end positioned to form a terminal and a removable plug closing the end of the casing.

8. A refillable fuse of the inclosed type comprising a tubular casing having a removable end closure, and a fusible element of strip form having an intermediate portion of its length within the casing and operative as a line protecting structure and an end portion extending through the casing and positioned to provide an exposed contact on the cylindrical surface of the casing.

9. A refillable fuse of the inclosed type comprising a tubular casing having a removable end closure of insulating material, and a fusible element of strip form having an intermediate portion of its length within the casing and operative as a line protecting structure and an end portion extending through the casing and positioned to provide an exposed contact on the cylindrical surface of the casing.

10. A refillable fuse of the inclosed type comprising a tubular casing having a removable end closure, and a fusible element of strip form having a portion operative internally of the casing as a line protecting structure and externally of the casing in the form of a fuse terminal with the terminal positioned on the cylindrical surface of the casing.

11. A fuse of the type disclosed in claim 7 characterized in that the plug is slotted to receive a portion of the fusible element.

12. A fuse of the type disclosed in claim 1, characterized in that the end closures extend within the casing and are slotted to receive portions of the fusible element.

13. A refillable fuse comprising a tubular casing, a slotted removable plug closing an end thereof, and a fusible element of strip form extending internally of the casing and externally of the casing with an intermediate portion extending into the plug slit, said external portion being positioned to form a terminal, said plug being movable in the direction of length of the casing in the presence of element disruption therein to serve to indicate the blown condition of the fuse.

14. A refillable fuse comprising a tubular casing having longitudinal slots, a slitted removable plug closing an end of the casing, a fusible element of strip form extending internally of the casing and externally of the casing with an intermediate portion extending into the plug, and securing means carried by the plug and extending into a casing slot.
- 10 15. A refillable fuse comprising a tubular casing having a longitudinal slot, a slitted removable plug closing an end of the casing, a fusible element of strip form extending internally of the casing and externally of the casing with an intermediate portion extending into the plug slit, means for securing the strip at the opposite end of the casing, a spring interposed between the plug and the casing end, and means extending into said casing slot and the plug and extending through the strip portion therein, to normally maintain the spring under tension, whereby disruption of the element within the casing will release the spring tension.
- 25 16. As a means for preventing maintenance of an arc in fuses of the inclosed type, a tubular casing of insulating material closed at its ends to form an inclosed chamber, said casing having a fusible element traversing said chamber and projecting laterally therefrom to provide line connection with the element externally of the casing when the fuse is positioned for active service and locate the chamber walls as an arc-disrupting formation intermediate the chamber and a stable conductor.
17. As a means for preventing maintenance of an arc in fuses of the inclosed type, a closed tubular casing of insulating material having a fusible element traversing the interior of the casing and projecting through the casing walls to provide a line connection with the element externally of the casing when the fuse is positioned for active service and locate the latter as an arc-disrupting structure between the interior of the casing and a stable conductor.
- 40 18. As a means for preventing maintenance of an arc in fuses of the inclosed type, a tubular casing of insulating material, a plug of insulating material closing an end thereof, and a fusible element of strip form extending internally of the casing and externally of the fuse with an intermediate portion extending into the plug, said plug having a formation to prevent arc-maintenance with respect to the strip portion within the plug, whereby a sustained arc is prevented from reaching the external portion of the strip.
- 45 50 55 60 65 19. A refillable fuse of the inclosed type comprising a tubular casing having an end closure slitted longitudinally, and a fusible element of strip form having an intermediate portion of its length within the casing and operative as a line protecting structure and an end portion extending into the plug slit and outwardly therefrom laterally and positioned to provide an exposed contact on the peripheral surface of the closure.

ALBERT F. DAUM.
